(57) **CLAIM**

The ornamental design for tweezers, as shown and described.

DESCRIPTION

FIG. 1 is a perspective view of an exemplary embodiment of tweezers according to the present invention.

FIG. 2 is a plan view thereof;

FIG. 3 is a right side view thereof;

FIG. 4 is a left side view thereof;

FIG. 5 is a front view thereof; and,

FIG. 6 is a rear view thereof.

The broken lines which define the bounds of the claimed design form no part thereof. All other broken lines are for illustrative purpose only and form no part of the claimed design.

1 Claim, 2 Drawing Sheets
